UNITED STATES PATENT OFFICE.

WILLIAM HAMILTON, OF ALLEGHENY, PENNSYLVANIA.

COFFIN-FASTENER.

SPECIFICATION forming part of Letters Patent No. 395,226, dated December 25, 1888.

Application filed September 6, 1888. Serial No. 284,745. (No model.)

To all whom it may concern:

Be it known that I, WILLIAM HAMILTON, of the city of Allegheny, in the county of Allegheny and State of Pennsylvania, have invented a new and useful Improvement in Coffin-Fastening Devices; and I do hereby declare the following to be a full, clear, and exact description thereof.

The main object of my invention is to provide improved means for attaching the lids and tops of caskets in such a way that the fastening devices may be used as hinges and that the lid may be raised thereon from either side.

It often happens in the management of funerals that caskets with hinged lids are inconvenient, because of the interference of the lid when raised with the furniture of the room, it being customary to have the foot of the casket directed toward the door. I obviate this difficulty by constructing caskets with hinged lids, which may be opened from either side and locked on either side. In a prior patent, No. 370,331, dated September 21, 1887, I describe and claim a casket of this form, wherein the lid is hinged to the casket by a hinge-lock composed of two leaves permanently hinged together, one of said leaves being fixed to the lid, and a movable bolt or lock which engages the other leaf, whereby the latter is detachably securable to the casket, so that it may be used either as a lock or as a hinge. In the device described and shown in that patent the bolt or lock is set in a recess 35 in the rim of the casket and engages a projecting stud or boss on one of the leaves of the hinge.

In the device which forms the subject of the present invention, and which is a subsidiary improvement on the device described and claimed in said patent, the bolt or lock is arranged on and carried by the detachable hinge-leaf. It also differs therefrom in that whereas in the said patent the bolt or lock operates lengthwise of the casket, in my present device the bolt operates transversely, and is movable by pulling on a small projecting cord or hand-piece.

The advantages derived from my present structure are increased strength and durability and neatness of appearance of the parts.

In the accompanying drawings, Figure 1 is

a transverse section through the lid and sides of the casket, showing my improved lock and hinge applied thereto. Fig. 2 is an enlarged 55 vertical section of the lock and hinge at one side of the casket. In this figure the parts are shown in full lines as indicating their relation when they are locked together, and in dotted lines as indicating their relation when 60 the lid is raised on the device as on a hinge. Fig. 3 is a vertical section on the line *x x* of Fig. 2, showing the lid of the casket raised. Fig. 4 is a bottom plan view of the leaves of the hinge detached from the lid, the leaves 65 being shown closed together. Fig. 5 is a top plan view of the keeper or socket, which is set in the rim of the casket.

Like symbols of reference indicate like parts in each figure. 70

In the drawings, 2 indicates the casket, and 3 is the lid or top. The upper edges of both sides of the casket are provided with my improved hinge and lock device, and as they are substantially the same in construction I shall 75 first describe a single side, and shall then indicate the relation of the devices on both sides to each other.

The lid is secured to the casket on both sides by means of the combined hinges and 80 locks shown in the drawings. Each of the latter has a hinge-plate, 4, which is permanently fastened to the under side of the lid by screws 5. Connected with the plate 4 by means of a pintle, 6, is a second plate, 7, which 85 is adapted to be folded into contact with the plate 4, as shown in Figs. 1, 2, and 4.

8 is a small boss or case which projects at right angles from the under side of the plate 7, and which is made hollow, so as to contain 90 a small movable spring-actuated bolt or catch, 9, the spring 10 of which tends to project a hooked portion at its forward end from the under side of the case. The shank of the bolt or catch has a rearwardly-projecting 95 stem, 11, which is adapted to have attached to it a cord or hand-piece, 12, by which it may be drawn back against the force of the spring 10, so as to retract the hooked portion within the case 8. In order to hold the bolt or catch 100 permanently in place in the plate 7, I prefer to make the plate of two slightly-separated leaves, which are rigidly fastened together by rivets 13. The upper edge of the bolt or catch

works in a slot made in the lower of the leaves of the plate 7, and the spring 10 is interposed between these leaves and is braced in its spring action by pins 14, as shown by dotted lines in Fig. 4. The bosses or cases 8 are adapted to enter sockets or locking-recesses 15, made in the rim of the casket. These recesses are cut in the rim of the casket at suitable intervals corresponding to the relative positions of the bosses or cases 8, and are preferably faced and lined with the device which I have illustrated in Fig. 5. This consists of a plate, 16, of metal, having a hole in the center, which is made by forcing out of the plate a tongue, b, which stands at right angles thereto. The plate 16 is screwed to the edge of the casket, and the tongue b projects down into the recess and holds the plate in place. Each of these recesses has a horizontal ledge or shoulder, c, formed by the rim of the plate 16, which affords means for the engagement of the hook of the bolt or catch 9. The operation of the device is as follows: When it is used as a lock for locking the lid to the rim of the casket, the parts occupy the relative positions shown in Figs. 1 and 2, the leaves 4 and 7 of the hinge being folded into a horizontal position in contact with each other, the case 8 projecting into the recess 15, the hooked portion of the catch or bolt 9 projecting from the case under the shoulder c in the recess, and the cord 12 being on the outer side of the casket. When in these positions, it is clear that the parts act as a perfect lock to the lid and hold it rigidly to the casket, and for the purpose of holding these parts more firmly together there are preferably several of the hinge-locks, two or more on each side of the casket. Now, if it be desired to raise the lid on the hinges on one side of the casket the bolts 9 of the hinge-locks on the other side are disengaged therefrom by pulling the bolts back by means of the cords 12, and the bolts 9 being then free from the locking-shoulder, the lid can be raised on this side freely from the casket. On the other side of the casket the hinge-leaves 7 are held to the casket by means of the bolts 9, and the lid therefore turns on the pinfiles 6 of the hinges which are so formed. In this way the lid may be raised from either side, the hinge-locks on one side acting as hinges on which the lid turns, while on the other side the hinges and the bolts are entirely detached from the casket and lift with the lid. When the hinges on both sides are locked to the casket, the lid is held down firmly in place. When the hinges on both sides are disconnected, the lid may be removed altogether.

The advantages of the invention will be ap-

preciated by those skilled in the art. The hinge-locks are simple in construction, durable, and are so inconspicuous as not to affect the desirable plainness and neatness of appearance of the casket. 65

My improved hinge-locks may be applied to use, as stated in the patent above mentioned, by using them on one side of the casket and applying to the other side any suitable fastening device or lock. Then the lid may always be raised on its hinge in one direction, and may be removed altogether by detaching the hinge, as above described.

I do not desire to limit myself to the exact form of the devices which I show and describe, since they may be varied by the skilled workman—for example, the parts may be transposed, the parts of the fastening device which I have shown on the casket being put on the lid and the parts on the lid put on the casket. 75 80

I am aware of Letters Patent No. 268,873 to Dayton, and do not claim what is therein shown and described; but

I claim—

1. The combination of the lid, the casket, and a hinge consisting of a leaf fixed to the under side of the lid, and a second leaf permanently hinged to the other and having attached to and carried by it a movable bolt or catch, whereby it may be detachably secured to the casket, substantially as and for the purposes described. 90

2. The combination of the lid 3, the plate 7, 95 permanently hinged to the lid and having a projecting bolt case or boss, 8, a movable bolt or catch secured therein and carried by the plate 7, and a casket having on its upper edge a socket adapted to receive the bolt case or boss and to engage the bolt or catch, substantially as and for the purposes described. 100

3. The combination of the lid 3, the plate 7, permanently hinged to the lid and having a projecting bolt case or boss, 8, a transversely- 105 sliding movable bolt or catch secured therein and carried by the plate 7, and the casket having on its upper edge a socket adapted to receive the bolt case or boss and to engage the bolt or catch, said bolt or catch having 110 an outwardly-projecting shank by which it may be moved and disengaged from the outside of the casket, substantially as and for the purposes described. 115

In testimony whereof I have hereunto set my hand this 5th day of September, A. D. 1888.

WILLIAM HAMILTON.
